UNITED STATES PATENT OFFICE

JOHN TAIT, WILLIAM TAIT, AND FRANCIS TAIT, JR., OF PHILADELPHIA, PENNSYLVANIA, ASSIGNORS TO HOWARD HOSIERY COMPANY, A PARTNERSHIP COMPOSED OF FRANCIS TAIT, SR., FRANCIS TAIT, JR., JAMES TAIT, WILLIAM TAIT, JOHN TAIT, ROBERT TAIT, SAMUEL TAIT, AND ELMER A. NAIGLE, OF PHILADELPHIA, PENNSYLVANIA

STRIPING ATTACHMENT FOR CIRCULAR SPRING-BEARD-NEEDLE KNITTING MACHINES

Application filed May 5, 1925. Serial No. 28,127.

Our invention relates to a new and useful improvement in circular spring beard needle knitting machines, and it relates more particularly to the novel attachment for such

5 knitting machines whereby a series of horizontal stripes of various colors may be knitted into any part, such as the foot or the leg, of the stocking or hose.

Our invention further relates to a new and 10 useful improvement in circular spring beard needle knitting machines whereby a series of horizontal stripes of various colors may be knitted into the body of a hose, spaced apart any desired distance and of any desired width 15 and whereby moreover the width of the stripes may be varied by predetermined increments throughout the length of the hose and whereby such variation may be accomplished automatically without any attention 20 on the part of the operator after the machine has been set.

Our invention further relates to a new and useful striping attachment for circular spring beard needle knitting machines, particularly 25 of the type described in U. S. Letters Patent No. 1,266,044, and while in the particular embodiment of our invention reference is made to the various parts of a standard spring beard needle knitting machine of the 30 type disclosed by said patent, yet it is to be understood that our novel attachment may be adapted to other knitting machines as well.

In circular spring beard needle knitting machines made heretofore, it has been customary to provide a single yarn change controlling cam drum having thereon a series of camming ribs, pivotally mounted lifting arms or "lifters" having the lower ends thereof resting on the camming ribs and having 40 their upper ends positioned beneath the pivotally mounted yarn feeding fingers so as to raise said fingers upward and out of operative position when the lower ends of said lifting arms or levers are engaged by the raised or active portion of the camming rib. This yarn change device, actuated by means 45 of a pawl and ratchet mechanism, actuated from the fashioning or timing shaft of the knitting machine, has been useful only in changing the yarn for the different parts of

the hose, thus permitting the use of a different grade, quality, thickness, or color of yarn, for the various parts of the hose, such as the welt, leg, pocket foot or toe pocket.

Our novel construction thus consists more 55 particularly in an oscillating arm carried by the outer end of the oscillating gear quadrant shaft of the knitting machine, a pin carried by said oscillating arm, an auxiliary cam drum rotatably mounted in suitable 60 bearings in proximity to the main control drum, said auxiliary drum having a ratchet wheel of suitable pitch secured to one end thereof, a pawl arm suitably mounted with respect thereto, an actuating link pivotally 65 connected to said pawl arm and having at its lower end a shoulder which is adapted to be engaged and encountered by said oscillating pin, whereby said actuating link will be forced upward so as to oscillate or rock 70 said pawl arm with each stroke of the oscillating arm, and thereby to revolve said auxiliary drum the distance of the pitch of said ratchet wheel, with each stroke of the oscillating arm. 75

Our invention further consists of a series of pivotally mounted auxiliary "lifters", controlled by said auxiliary drum, for raising the yarn guide fingers out of operative or knitting positions at predetermined intervals, either by direct engagement with the respective yarn guide fingers or through the engagement with the corresponding main lifters. 80

Our invention further consists of novel 85 means for retaining said auxiliary control drum inoperative during the formation of certain portions of the hose, where no striping is desired, which means consists more particularly in a cam of suitable contour carried by the timing shaft of the knitting machine, a rod pivotally secured to the auxiliary drum ratchet actuating link at one end thereof and slidably upon a pivot carried by said cam and a follower roller carried by said rod, 90 in alignment with the camming surface of said cam, whereby said actuating link will be raised by said cam during the formation of certain portions of the hose where the striping is to be omitted, so as to bring the shoul- 95 100

der on said actuating link out of alignment with the oscillating pin, thereby preventing the engagement of said link by said pin, as the latter oscillates to and fro.

- 5 Our invention further consists of novel means to vary the width of the stripes that would otherwise be produced by the uniform intermittent rotation of the auxiliary control, by acting upon the actuating link at varied intervals, so as to raise the shoulder at its lower end, out of alignment with the oscillating pin, so as to retain the auxiliary control drum stationary over a greater interval, or for a greater number of courses.
- 10 15 This latter means consists more particularly in a width controlling cam disc, suitably mounted upon a pivot, said cam disc preferably having an adjustable contour, a suitable projection carried by said actuating link in alignment with said cam disc and adapted to be encountered thereby, and suitable pawl and ratchet mechanism for actuating said cam disc either constantly or at certain predetermined intervals.
- 20 25 Our invention further consists in novel means to actuate yarn severing and clamping devices with each movement of the actuating link, thereby to sever each of the yarns as it is removed from the hose in the striping operation.

To the above ends our invention consists of the novel means illustrated in the annexed drawings, and hereinafter described and claimed, by which the main objects of the invention set forth above, as well as other objects that will hereinafter be described, are attained.

For the purpose of illustrating our invention, we have shown in the accompanying drawings forms thereof which are at present preferred by us, since they will give in practice satisfactory and reliable results, although it is to be understood that the various instrumentalities of which our invention consists can be variously arranged and organized and that our invention is not limited to the precise arrangement and organization of these instrumentalities as herein shown and described.

30 Referring to the drawings in which like reference characters indicate like parts:

Figure 1, represents a perspective view of a novel striping attachment for circular spring beard needle knitting machines, embodying our invention.

Figure 2, represents a perspective view of the yarn severing and clamping device on an enlarged scale.

Figure 3, represents a side elevation of our novel device.

Figure 4, represents a section on line 4—4 of Figure 1, showing the auxiliary control drum in the striping position.

Figure 5, is a similar view showing the auxiliary control drum in a position adapted

to knit the body of the hose, that is, a position in which the striping yarn had been removed from the knitting operation.

Figure 6, represents a side elevation of the width controlling cam plate and ratchet wheels.

Figure 7, represents a section on line 7—7 of Figure 1.

Figure 8, represents a view in elevation of a hose having a series of horizontal stripes 75 of uniform width, as produced by our novel device.

Figure 9, represents a similar view in elevation of a hose having a series of stripes of varying width, as produced by our novel 80 device.

In Figure 1, we have shown a portion of the frame 1 of the conventional circular spring beard needle knitting machine, while the stationary ring 2 supports the spring beard depressor. Similarly 3 is the outer left hand end of the "timing" or fashioning shaft of the knitting machine, which, as is well known in the art, is revolved intermittently by the pattern chain and the pawl and ratchet drive cooperating therewith. On the end of this shaft we have secured a cam 4 having certain low and certain high cam surfaces in proper spaced relation to the patterning devices actuating the shaft 3 within 95 the machine. By means of the cam 4, the striping may be eliminated during the knitting of certain parts of the hose, where the stripes are not desired, and may be again inserted during the knitting of those portions 100 of the hose in which the stripes are desired. Usually the stripes are only desired in the tubular portion of the hose, between the welt and the heel, and possibly on the instep or the foot of the stocking. In the particular 105 illustration of the cam 4, shown in the figures, the low or active striping portions 5 and 6 of the cam are designed to effect a constant striping during the knitting of the leg and foot portions respectively of the hose, while the high portions 7 and 8 of the cam, are adapted to eliminate the stripes from the welt, toe and from the heel portions respectively, of the hose.

The oscillating shaft 9, carrying the oscillating gear quadrant of the machine, not shown in the drawings, extends through the frame 1, and carries at its outer end, an oscillating arm 10, carrying a pin 11, at a suitable distance from the center of oscillation.

We further secure to the frame 1 of the machine, a stud or pivot 12, on which is mounted the width controlling cam plate 13, as well as the idle and active ratchet wheels 14 and 15 respectively. We further provide 125 a pawl 16 pivoted on the oscillating arm 10, at a point 17, said pawl 16 being of sufficient width to be in operative alignment with each of the two ratchet wheels 14 and 15, so that it may engage both.

The yarn control cam drum 18, forming part of the conventional knitting machine of this type, having the various camming ribs 19, is actuated intermittently, at predetermined intervals, by means of the pawl arm 20 and the corresponding ratchet wheel 21, actuated by the connecting link 22, which in turn is driven by the pattern mechanism. The control cam drum 18, engages the lower fol-

10 lower ends 23, of the yarn guide lifters 24 and 25, which are pivotally mounted upon a common pivot 27, thereby to raise and lower, at predetermined periods, the respective yarn guide fingers 28 and 29, so as to interchange 15 the yarns carried by these guides for the various parts of the hose, as mentioned hereinbefore.

The yarn shearing and clamping devices shown particularly in Figure 2, as is well known in the art, consist of the stationary shearing blade 30, the movable and spring pressed shearing blade 31, which is held against the edge of the stationary shearing plate 30, by the spring 32, and is carried by 25 the pivotally mounted shearing arm 33. The clamping member 34 pivoted at 35 and pressed by the spring 36 is also of the usual construction.

The severing and clamping devices above referred to, are tripped by means of the two tripping rocker arms 37 and 38 respectively, which are pivotally mounted at points 39 and 40 respectively. The tripper 37 is actuated with each movement of the main control drum 18 by means of the horizontal rod 41 rigidly carried by the link 22, and the link 42 interconnecting the lower end of the arm 37 with said rod 41. The upper end of the tripping arm 37 encounters a pivotally mounted dog 40 43, carried by the arm 44, whereby the same is first raised upon the first half of the stroke of the arm 37, so as to set the shearing and clamping devices and whereby the same is released so as to trip the shearing and clamping device upon the return stroke of the arm 37, as is well known in the art.

The yarn change devices above referred to, consisting chiefly of the fingers 28 and 29, are shown particularly in Figure 1. The lifters 24 and 25 are adapted to effect a change of yarns for the various parts of the hose only. While for the purposes of illustration, we have shown in the figures only two yarn guide fingers 28 and 29, it is to be understood that the number is usually more, and may be increased to any desired number, equal to the number of different yarns used.

In order to effect an interchange of two yarns within any part of the hose, such as the leg for instance, we provide the auxiliary cam drum 46 and ratchet wheel 47 secured to one end thereof, and suitably mounted upon the pivot shaft 48, which is carried in suitable brackets, not shown in the drawings.

65 The ratchet wheel 47 is provided with a suit-

able number of teeth, depending upon the relative width of stripes desired. The pawl arm 49 is also pivotally mounted upon the pivot shaft 48 and has an upper handle 50 for manual operation, and carries a spring pressed pawl 51, mounted in the horizontal extension 52 of the pawl arm. We further provide a series of auxiliary lifters 53 and 54 pivotally mounted upon a common pivot 55 and having their lower ends in operative alignment with the corresponding cam surfaces or ribs 56 and 57. The lifters 53 and 54 are bent into suitable form so as to project beneath the corresponding main lifters 24 and 25 so as to raise the same, and hence raise the corresponding yarn guide fingers 28 and 29 when the auxiliary lifters are acted upon by the auxiliary control cam drum 46. By this means it is possible to place any two, or more, of a series of yarn guide fingers, such as 28 and 29 illustrated in Figure 1, under the common control of two independently actuated, sets of lifters; that is, a set of main lifters and a set of auxiliary lifters. Assuming the finger 28 to carry the body yarn for a particular part of the hose, such as the leg for instance, which we assume to be silk, and the finger 29 to carry another silk yarn, of a different color however, to produce a colored stripe, it is seen that while the main control drum 18 leaves the body yarn carried by 28 in the knitting position throughout the formation of the leg, the auxiliary control drum 46, through its auxiliary lifters 53 and 54, will raise the body yarn 28 out of the hose and drop the striping yarn, carried by 29, in its place, for a predetermined number of courses.

The relative widths of the colored stripes, where such stripes are uniform throughout and are uniformly spaced from each other, may be controlled entirely by the relative lengths of the two camming surfaces 56 and 57 respectively. In the particular illustration shown in the drawings the cam 56, acting upon the body yarn, lifts the same out of the hose only for a relatively short distance, approximately one tenth of the width of the body stripe and the cam surface 57 as will be seen from Figures 4 and 5, is cut away an amount just sufficient to drop the colored yarn in place, while the body yarn is out. The lifting out of one yarn, however, is always preceded by the lowering of the other yarn in order to interknit the yarn ends.

In producing stripes of uniform width and uniformly spaced from one another, the camming surfaces 56 and 57, properly proportioned, serve the purpose; the auxiliary control drum 46 being turned one or several notches or teeth on the ratchet wheel 47, with each stroke of the oscillating arm 10, as brought out hereinbefore. This is effected

through the actuating link 58, pivotally secured at its proper end to the pawl arm 49, at a point 59, and having the shoulder 60 at its lower end in alignment with the oscillating pin 11. Thus with each stroke of the arm 10, the pin 11 encounters the shoulder and raises the actuating link 58, and hence moves the pawl arm 49, so as to rotate the ratchet wheel 47 and the auxiliary drum 46 one or several teeth, depending upon the stroke of the pin 11. Since in practice there are approximately four courses knitted for each stroke of the oscillating arm 10, since the same is carried upon the oscillating shaft 9 of the knitting machine, which moves with the oscillating gear quadrant of the machine, it is seen that by properly proportioning the relative lengths of the cam 56 and the cam 57, it is possible to produce horizontal stripes 20 of any given number of courses, in multiples of 4 or whatever number of courses correspond to one oscillation of the shaft 9.

In order to effect the severing and clamping of the yarn, as it is removed from the hose, we provide, as mentioned hereinbefore, the auxiliary tripping arm 38, pivotally mounted at 40, and adapted to engage the auxiliary dog 61 carried by a rear extension of the arm 44, which we provide for this purpose. The tripping arm 38 is actuated by the transverse rod 62, adjustably mounted upon the bracket 63, by means of the nut 64; said bracket 63 being secured to the actuating link 58, as shown in Figures 1 and 3. The link 65 interconnects the rod 62 with the lower end of the arm 38. By this means the severing and clamping devices of the knitting machine will be actuated not only for every movement of the main control drum 30 of the knitting machine, but also for every movement of the auxiliary control drum 46 as well.

In order to eliminate the striping in certain parts of the hose, that is, in order to eliminate any interchanging of a colored yarn with the body, in certain parts of the hose, such as the heel, toe and welt, we provide a cam 4, upon the end of the pattern or timing shaft 3 of the knitting machine, as mentioned hereinbefore. We further provide the follower rod 66, pivotally secured to the actuating link at 67 and having an elongated slot or opening 68, in its lower end. The pivot pin 69 fixed to the center of the cam 4 and having the flange 70, passes through the slot 68 so as to retain the rod 66 in radial alignment with the center of rotation of the cam 4 at all times. The follower roller 71 is pivotally mounted upon the follower rod 66, at a point 72, in alignment with the camming edge of the cam 4. By properly proportioning the high and low portions of the cam 4, so as to engage the follower roller 71 and to raise the rod 66, during the formation of those portions of the hose, in which

no striping is desired, the rod 66 will be raised, thereby raising also the actuating link 58, into an inactive position as shown in Figure 3; in which position the oscillating pin 11 is out of alignment with the shoulder 60. In this position no striping will take place, since the auxiliary drum 46 is not active. As brought out hereinbefore, the cam 4 in the particular illustration shown, is provided with four distinct camming portions. The high or "inactive" portion 7 corresponding to the welt and toe, the former being the beginning of the hose, while the latter forming the end of the same; the low or "striping" surface 5 corresponding to the leg; the high or "inactive" surface 8, corresponding to the heel; and the low or "striping" surface 6 corresponding to the foot.

In order to produce stripes of varying widths, we may use the two camming ribs 73 and 74 instead of the ribs 56 and 57, said ribs 73 and 74 having alternate high and low portions of uniform length and all uniformly spaced, which, in the normal operation of the auxiliary control drum 46, would produce stripes of the body and stripes of the colored yarn, of uniform and equal width. In using the ribs 73 and 74 the auxiliary lifters 53 and 54, shown in Figure 1, are also replaced with similar auxiliary lifters, of a greater width however, so that their follower ends will be in operative alignment with the respective ribs 73 and 74. In producing the stripes of varied width however, the actuating link 58 is raised into an inactive position for certain predetermined and unequal intervals of time, while the body yarn is being knitted, thereby knitting more of that yarn than of its substitute colored yarn. By this means the stripes of the body yarn and the stripe of the colored yarn may be increased or decreased corresponding amounts, as desired, by merely raising the actuating link 58 into an inactive position with respect to the oscillating pin 11, at suitable intervals.

This is accomplished by means of the cam disc 13, pivotally mounted upon a stud 12, as mentioned hereinbefore, and actuated by the pawl 16, also carried by the oscillating arm 10. The cam plate 13 is preferably of an adjustable type, having the high and the low peripheral camming lugs 75 and 76 respectively, detachably secured to it in any suitable manner. The actuating link 58 is further provided with a slight projection 77, in alignment with the camming lugs 75 and 76. Thus, whenever a high camming lug 75 is brought around to the projection 77, it will encounter the same and again raise the actuating link 58 into an inactive or inoperative position with respect to the oscillating pin 11.

In Figures 1, 3, 6 and 7 we have shown means, whereby the cam disc 13 will be actuated intermittently instead of constantly,

with each movement of the pawl 16. This means consists chiefly of the idle ratchet wheel 14, having a suitable number of high teeth 78 and a suitable number of low teeth 79, properly distributed throughout its circumference. The cam disc 13 on the other hand is secured to the ratchet wheel 15 which is of a slightly smaller diameter than the high teeth of the idle ratchet wheel, being of the same diameter as the lower teeth 79. Thus the active ratchet wheel 15 will only be engaged by the pawl 16 when the latter drops into one of the low teeth 79, and will not be moved while the pawl 16 is engaging one of the high teeth 78. Thus also, the cam disc 13 will only be moved a notch when the pawl 16 drops into one of the low teeth 79 of the idle ratchet wheel 14.

It is thus seen that by the proper positioning of the low teeth 79, and a proper adjustment of the high and low lugs 75 and 76 respectively, it is possible to increase or decrease the width of the stripes in any part of the hose, by any desired increments; the latter depending upon the distances between the successive high lugs 75. In the particular illustration shown in the drawings, it is seen that the high lugs 75 are spaced apart by uniformly increasing distances, thereby increasing the width of the stripes constantly, by equal increments.

It is thus seen, that we may either produce a series of uniform stripes through any portion of a hose, or we may produce stripes of varying width. Similarly, we may produce a series of individual stripes of a single color in the hose, or we may place several differently colored stripes in the hose, alongside of each other, or spaced apart from each other, as the case may be.

Thus, to produce a simple uniform stripe with one striping yarn, it is only necessary to have one striping yarn guide finger 29, which is raised and lowered by means of the main lifter 25 and the auxiliary lifter 54, as shown particularly in Figure 1. The striping yarn finger 29, is then substituted in place of the body yarn finger 28 at intervals determined by the relative extents of the corresponding camming ribs 56 and 57, as brought out hereinbefore. For such uniform striping with a single striping yarn, the stripe width controlling cam 13, carried by the pivot shaft 12 and the actuating pawl 16 therefore, are not necessary. In that case therefore, the pawl 16 is merely thrown back into an inoperative position, and the striping is effected through the actuating link 58 and the oscillating arm 10 as mentioned hereinbefore.

Similarly, if it is desired to produce a uniform striping, in only certain portions of the hose, then it is necessary to employ the striping cam 4, whereas, if the striping action is to continue throughout the entire hose, then the cam 4 can be dispensed with, by merely

disconnecting the follower rod 66 from the actuating link 58.

It is further to be understood that several differently colored striping yarns, or several striping yarns of different qualities, may be used, by merely providing a plurality of striping yarn fingers 29, mounted along the side of the one shown in Figure 1 and providing corresponding lifters 25 and 54 and camming ribs 57 on the cam control drum 46. In using the width controlling cam plate 13, as brought out hereinbefore, it is only necessary to so position the high camming lugs 75 around the periphery of the cam as to engage the projection 77 on the actuating link 58, at varied intervals and to retain said actuating link out of operative engagement with the arm 10, for varied periods of time, while either a body yarn finger or a striping yarn finger is in the knitting position. The arrangement of the lugs 75 as well as the spacing of the low teeth 79 in the idler ratchet wheel 14, is determined entirely by the increments desired in widths of the successive body stripes and colored stripes. In Figure 9 we have illustrated a hose having a series of stripes of varying widths, as produced with the aid and cooperation of the width controlling cam 13, whereas, in Figure 8 we have shown a hose with uniform stripes as produced without the aid of the width controlling cam 13, but only with the aid of the auxiliary cam drum 45 and the striping cam 4. Due to the fact that the yarn change control drum is timed with relation to the forming or patterning operations in the knitting of the hose, that is, it is timed with relation to different parts of the hose, it has been impracticable therefore to effect any periodic recurring changes of the yarns for a given

number of courses within any part of the hose so as to produce stripes of different colored yarns. By our novel construction, the yarn guide fingers carrying the various yarns are placed under the common control of two independently actuated yarn change control cam drums, the main drum to effect a change of yarns for the various parts of the hose and the auxiliary control drum to effect a periodic change of yarns within any desired parts of the hose, so as periodically to substitute a differently colored yarn for the body yarn, thereby to produce colored stripes, said auxiliary control drum being actuated independently of the main control drum, so that it may effect the desired striping of the hose, in any portion thereof, independently of the patterning or fashioning operation.

It will now be apparent that we have devised a novel and useful construction of a striping attachment for circular spring bearded needle knitting machines which embodies the features of advantage enumerated as desirable in the statement of the invention and the above description, and while we have, in the

present instance, shown and described preferred embodiments thereof which will give in practice satisfactory and reliable results, it is to be understood that such embodiments 5 are susceptible of modifications in various particulars without departing from the spirit or scope of the invention or sacrificing any of its advantages.

Having thus described our invention, what 10 we claim as new and desire to secure by Letters Patent is:—

1. The combination of a spring beard needle knitting machine including a main control cam drum, a body yarn guide finger, 15 a striping yarn guide finger, an auxiliary control cam drum, finger lifters intermediate said yarn guide fingers and said control drum for raising and lowering said fingers in opposite directions, a pawl and ratchet co-operating with said control drum to revolve 20 the same predetermined amounts, an actuating link operatively connected with said pawl, an auxiliary arm, means to effect engagement between said arm and said actuating link with each stroke of the former, a timing shaft, a striping cam carried by said timing shaft, having two different camming surfaces, corresponding respectively to those 25 portions of the hose to be striped, and those portions of the hose to be knitted without any striping, follower means intermediate said striping cam and said actuating link for displacing the latter out of an engaging alignment with said auxiliary arm, and a width 30 controlling cam cooperating with said auxiliary control cam drum to vary the action of the latter by any desired increment.

2. The combination of a spring beard needle knitting machine including a main control 40 cam drum, a body yarn guide finger, a striping yarn guide finger, an auxiliary control cam drum having peripheral camming ribs corresponding to each of said yarn guide fingers, finger lifters intermediate said yarn 45 guide fingers and the corresponding camming ribs on said drum, whereby one of said fingers is raised from, while the other is lowered into, a knitting position by said drum, a width controlling cam coacting with said auxiliary 50 cam control drum to vary the action of the latter by any desired increment, and means intermittently to revolve said auxiliary control cam drum a predetermined amount for any desired number of courses knitted by said 55 knitting machine, including a link adapted to actuate said drum, and a plurality of cam surfaces for intermittently rendering said link inoperative.

3. The combination of a spring beard 60 needle knitting machine including a main control cam drum, a body yarn guide finger, a striping yarn guide finger, an auxiliary control cam drum having peripheral camming ribs corresponding to each of said yarn guide 65 fingers, finger lifters intermediate said yarn

guide fingers and the corresponding camming ribs on said drum, whereby one of said fingers is raised from, while the other is lowered into, a knitting position by said drum, means intermittently to revolve said auxiliary control cam drum a predetermined amount for any 70 desired number of courses knitted by said knitting machine including a link adapted to actuate said drum and a plurality of cam surfaces for intermittently rendering said link inoperative, and width controlling means for said auxiliary drum, whereby the latter may be retained inactive for varied intervals of time, while either the body yarn finger or the striping yarn finger is in the knitting position. 75

4. The combination of a spring beard needle knitting machine including a main control cam drum, a body yarn guide finger, a striping yarn guide finger, an auxiliary control cam drum to raise and lower, out of 80 and into the knitting position, said yarn guide fingers in opposite directions, a width controlling cam cooperating with said auxiliary control cam drum, whereby the latter is rendered inactive for successive intervals of pre- 85 determined and varied numbers of courses of said knitting machine, and means for revolving said auxiliary cam control drum including a link adapted to actuate said drum, and a plurality of cam surfaces for intermittently 90 rendering said link inoperative.

5. In a device of the character stated, a plurality of yarn guide fingers, a main control cam drum, pivotally mounted lifters co-operating with said main control drum and in 100 alignment with corresponding yarn fingers to raise certain of said yarn fingers out of an operative or knitting position and to lower other yarn fingers in their places, for the various parts of the hose, an auxiliary control drum, auxiliary lifters cooperating with the same, adapted to raise a certain one of said yarn 105 fingers out of an operative position and to lower another yarn finger in its place, means to actuate said auxiliary control drum periodically with a given number of courses of the knitting machine including a link operated by a source of power and adapted to revolve said drum, a timing shaft, a cam carried by said shaft adapted to render said link 110 intermittently inoperative, and a width control cam coacting with said link for rendering said auxiliary control drums inoperative during the knitting of certain portions of the 115 hose.

6. The combination, in a knitting machine, of a plurality of yarn guide fingers, lifters to actuate the same, a main controlling cam drum to operate said lifters, an auxiliary control drum, auxiliary lifters adapted to actuate said yarn guide fingers independently of the main controlling drum, means to actuate said auxiliary drum, a width cam coacting with the actuating means of said auxiliary 125 drum to vary the action of the latter by any 130

desired increment, means for rendering said auxiliary drum inoperative during the knitting of certain portions of the hose and for rendering the same operative during the knitting of other portions of the hose, including a link adapted to actuate said drum, and a plurality of cam surfaces for intermittently rendering the said link inoperative.

7. In a knitting machine of the character stated, a main control cam drum, an auxiliary control cam drum, auxiliary finger lifters co-operating therewith, means to actuate said auxiliary drum, including an actuating link driven by a source of power, and a timing cam adapted to render said link inoperative during the formation of certain parts of the hose, and the width control cam cooperating with said actuating means to vary the action of said auxiliary cam drum by any desired increments.
